(57) **CLAIM**

The ornamental design for a toothbrush shaped toothpaste package, as shown and described.

DESCRIPTION

FIG. 1 is a perspective view of a toothbrush shaped toothpaste package;

FIG. 2 is a top plan view thereof;

FIG. 3 is a left side view thereof;

FIG. 4 is a right side view thereof;

FIG. 5 is a front end view thereof; and,

FIG. 6 is a back end view thereof.

The broken line showing of the indicia "Tear Here" in FIG. 1 is for illustrative purposes only, and forms no part of the claimed design.
